UNITED STATES PATENT OFFICE.

FRANK MOSSBERG, OF ATTLEBORO, MASSACHUSETTS, ASSIGNOR TO MOSSBERG
PRESSED STEEL CORPORATION, OF ATTLEBORO, MASSACHUSETTS, A COR-
PORATION OF MASSACHUSETTS.

PICKER STICK.

Application filed October 31, 1922. Serial No. 598,115.

To all whom it may concern:

Be it known that I, FRANK MOSSBERG, a citizen of the United States, residing at Attleboro, in the county of Bristol and State of Massachusetts, have invented certain new and useful Improvements in Picker Sticks, of which the following is a specification.

This invention relates to metal picker sticks of the type employed to drive the shuttle across the loom; and the object of this invention is to provide a picker stick of this character formed of metal and in such shape that it will be very light in weight and somewhat yieldable in its action upon coming forcibly in contact with the shuttle. In other words, to form a picker stick of metal having the maximum rigidity consistent with light weight and yet have the required flexibility to yieldably absorb shocks of engaging the shuttle to throw it across the loom.

A further object of this invention is to provide a spring through which the operating power is transmitted to the picker stick.

A still further object of the invention is to provide a cup-shaped holder and secure the same to the operating end of the stick and in which a buffer or pad of leather or other shock-absorbing material is mounted.

With these and other objects in view, the invention consists of certain novel features of construction, as will be more fully described, and particularly pointed out in the appended claims.

In the accompanying drawings:

Figure 1 is a front edge view of my improved metal picker stick which is formed in the shape of a channel bar, and showing the edges of the bar as crimped or wavy along their length.

Figure 2 is a side elevation of my improved metal picker stick showing a spring on the back of the stick through which power is transmitted to the stick.

Figure 3 is a view of a portion of the back edge of the stick and showing the spring mounted thereon.

Figure 4 is an enlarged sectional view

on line 4—4 of Figure 2, showing the cup-shaped member in which the leather bumper 50 is carried.

Figure 5 is a perspective view of the spring through which the operating power is yieldingly transmitted to the picker stick.

Figure 6 is a perspective view of the leather pad which is secured to the back of the spring.

Figure 7 is a view of my improved metal picker stick and showing the slot therein by 60 means of which the buffer member may be adjusted vertically on the stick.

It is found in the practical use of wooden picker sticks that they often break, and in addition to seriously interfering with the continuous action of the loom, the shuttle when the stick breaks, sometimes stops in a position to not only break down the warp threads, but also to break other parts of the mechanism, and to obviate this difficulty, I 70 have provided a picker stick formed of sheet metal and preferably bent into the form of angle iron whereby the stick will be substantially as light in weight as wood and in order to render it yieldable or somewhat 75 resilient like that of the wooden stick, I crimp or otherwise treat or shape the stock of the stick whereby the stick will flex and provide the necessary elasticity or yieldability for properly driving the shuttle 80 across the lay; and the following is a detailed description of one construction of picker stick by which these results may be accomplished:—

With reference to the drawings, 10 designates my improved metal picker stick which is preferably formed of sheet metal channel iron of substantially U-shape in cross section having a back wall 11 and two opposite side walls 12. This stick is preferably tapering, that is, the side walls are deeper at the lower end 13 of the stick than at the upper or swinging end 14 thereof. The back wall at the lower end of the stick is preferably rounded for the purpose of receiving a strap 15 from the spring reel 16

to return the stick after having been rolled on its rocker-shoe 17 under impulse of its actuating mechanism (not shown), through a strap or link 18. At the upper end of this 5 picker stick, I preferably turn the edges 19 of the side walls inwardly towards each other for a short distance down along the stick to provide a broad, bearing surface to engage the stop for limiting the forward stroke of the 10 stick, these inturned edges also serving as a broad bearing for the cup member 20 on which a leather buffer 21 is mounted, which cup may be secured in position by a bolt 22 that passes through a slot 23 in the back 15 plate 11 of the stick.

It is found in practice essential in the construction of a metal picker stick of this character to render the same more or less yieldable at the time of its impact or engagement with the shuttle, and to accomplish this in a simple and effective way, I have crimped or stretched the edges 24 of this channel bar forcing them out of a straight line into a wavy line, whereby 25 when a shock is received on the stick by its impact against the shuttle these edges will have a tendency to straighten out and so permit the stick to yield, flex or bend slightly backward.

30 By this construction, a metal picker stick may be formed substantially as light in weight as wood and with the necessary resiliency to impart a quick and snappy action to the shuttle in throwing it across a loom 35 which would not be the effect if the shuttle were engaged by a dead hammer blow.

In some instances where greater flexibility is required than that in the stick itself, I mount and secure a bow type of flat spring 40 25 upon the back of this stick and secure its upper end to the stick by means of a bolt 26, the lower end of the spring being preferably slotted as at 27 to permit an endways movement while flexing, the slot being 45 engaged by a loose rivet 28. I also preferably form lateral notches 29 in the edges of this spring through which the link 18 passes, a leather cushioned pad 30 and a hard rubber or fiber pad 31 being positioned 50 to be engaged by the link to soften its operating blow upon the picker stick through the spring.

I have shown and described the picker stick as operating with the channel portion 55 open on its inner side, but this stick may operate in the reverse position of desired, that is, in position so that the thrust may be received on the opposite side or face of the stick, if desired.

60 My improved form of picker stick is very simple, practical and inexpensive in construction and effective in its action and by its use a metal picker stick is provided which which performs all of the functions 65 of a wooden picker stick and by its use the

operating life of the picker stick is materially increased.

The foregoing description is directed solely towards the construction illustrated, but I desire it to be understood that I do not wish to be restricted to making the stick in channel form as the stick may be formed of sheet metal bent into any angular form or any other form to possess the required lightness of weight and flexibility 75 without departing from the spirit and scope of my invention which is defined and limited only by the terms of the appended claims.

I claim:

1. A sheet metal picker stick of angular form in cross section having walls set at substantially right angles to each other, one of said walls intermediate its ends being laterally offset out of the plane of the end 85 portions thereof.

2. A sheet metal picker stick of angular form in cross section having bottom and side walls, the latter wall having laterally offset portions to render the stick yieldable 90 in the plane of its oscillation.

3. A sheet metal picker stick bent into channel form and having portions of its side walls offset laterally to render the stick yieldable in line with its thrust. 95

4. A sheet metal picker stick bent into channel form and having the edges of its side walls laterally offset in opposite directions to render the stick yieldable in the plane of its oscillation. 100

5. A metal picker stick formed of a channel bar having side walls with laterally offset edges and having inturned edges at one end to form a bearing for a picker.

6. A sheet metal picker stick of angular form in cross section having one wall disposed in a plane at right angles to that of the thrust of the stick and having another wall set substantially parallel to the plane of thrust, portions of said latter wall being offset laterally from the plane of the rest of said wall to render it yieldable in the direction of its width. 110

7. A sheet metal picker stick of angular form in cross section having one wall disposed in a plane at a right angle to that of its plane of oscillation, and another wall set parallel to the plane of oscillation, portions of the free edge of said latter wall being offset out of the plane of the rest of said wall to render it yieldable in a plane parallel with that of its oscillation. 115

8. A sheet metal picker stick formed with a wall at a right angle to the plane of its oscillation and another wall disposed in a plane parallel to that of its oscillation and having one edge integral with the first mentioned wall, the free edge of the last mentioned wall being offset laterally from the plane of the rest of that wall. 120 125 130

9. A sheet metal picker stick bent into channel bar having crimped or wavy edges channel form and crimped to render it and having inturned edges to form a bearing for a picker.

10

10. A sheet metal picker stick bent into channel form and having its edges crimped to render it yieldable.

11. A metal picker stick formed of a

In testimony whereof I affix my signature.

FRANK MOSSBERG.
